CLAIM

We claim the ornamental design for a scented flexible bag with pressure-sensitive adhesive strip for disposal of feminine hygiene products, as shown and described.

DESCRIPTION

FIG. 1 is a perspective view of a scented flexible bag with pressure-sensitive adhesive strip for disposal of feminine hygiene products showing our new design;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof, the bottom plan view being identical thereto; and,

FIG. 6 is a bottom plan view thereof.
